tion July 11, 1973, Ser. No. 378,166

Term of patent 14 years

Int. Cl. D21—02
U.S. Cl. D34—5 GH

FIG. 1 is a perspective view of a golf putter head showing my new design.

FIG. 2 is a top plan view of the golf putter head shown in FIG. 1.

FIG. 3 is a front elevational view of the golf putter head shown in FIG. 1.

FIG. 4 is a rear elevational view of the golf putter head shown in FIG. 1.

FIG. 5 is a side elevational view of the golf putter head as seen from the left of FIG. 2.

FIG. 6 is a side elevational view of the golf putter head as seen from the right of FIG. 2.

The distinctive feature of my design invention for a golf putter head is the prominent "T" member having the arms thereof at the top and front of the putter head, the freestanding leg portion of said "T" member extending rearwardly therefrom.

This is a division of the copending design application of the same inventor, Ser. No. 226,385, filed Feb. 14, 1972, and entitled Golf Putter Head, now abandoned.

I claim:

The ornamental design for a golf putter head, as shown and described.
